UNITED STATES PATENT OFFICE.

BERTRAND A. PARKES, OF PHILADELPHIA, PENNSYLVANIA, ASSIGNOR TO THE PHILADELPHIA DRYING MACHINERY COMPANY, OF PHILADELPHIA, PENNSYLVANIA, A CORPORATION OF PENNSYLVANIA.

DRYING MACHINE.

Application filed October 22, 1920. Serial No. 418,719.

To all whom it may concern:

Be it known that I, BERTRAND A. PARKES, a citizen of the United States, residing in Philadelphia, in the county of Philadelphia and State of Pennsylvania, have invented certain new and useful Improvements in Drying Machines, whereof the following is a specification, reference being had to the accompanying drawings.

10 The invention relates to drying machines and more particularly to that type wherein the articles being dried are constantly subjected to a draft of air set up by suitable propelling means. Difficulty has heretofore been experienced in drying various articles of manufacture such, for example, as china, porcelain, crockery, etc., on account of their tendency to fracture or crack under internal stresses resulting from irregularities in the course of the treatment. The most important of the contributory causes of such irregularities, I have found to be due to variations in the intensity or velocity of the drying medium in different portions of the field or space through which the articles are passed during the treatment. The above argument will perhaps be made somewhat clearer by considering for a moment the conditions obtaining in a typical drying machine of the sort to which my invention appertains. In such machines, rotary fans are ordinarily employed in propelling the air. As is well known, under the characteristic operation of fans of this type, the velocity of the whirl induced by them is greater at the periphery than at the centre, as a consequence of which, the drying power of the air in different portions of the fan field varies accordingly. Thus as the articles being dried are passed through the fan field, some of them are dried at a much faster rate than others. While this consideration may be readily ignored in a great many instances of drying, it is, as can be readily understood from the foregoing, of the utmost importance in the treatment of wares of the aforesaid kinds.

50 The object of my invention is to overcome the difficulty above pointed out, and this I accomplish by controlling the flow of the drying medium in such manner as to compensate for irregularities in the current as it comes from the propelling means, and at

the same time, modifying the humidity of the air by application of additional moisture 55 at the critical regions.

The advantages of my invention will become readily apparent from the detailed description which follows.

In the drawings, Fig. I is a longitudinal 60 sectional elevation of a drying machine conveniently embodying my invention.

Fig. II is a cross section of the same viewed in the direction of the arrows II-II 65 in Fig. I; and

Fig. III is a diagrammatic plan view upon a somewhat reduced scale.

Fig. IV is a sectional view of a fragmentary portion of the structure showing a slight modification of baffle plates for controlling flow of air through the machine. 70

The machine herein shown comprises an enclosure comprehensively designated by the numeral 1, this enclosure consisting of a structural framework which is covered by 75 sheet metal paneling according to the practice usually followed in this art. Moving in a general longitudinal direction through the enclosure 1, is a conveyor which consists of a pair of spaced sprocket chains represented conventionally at 2-2 which are guided over sprocket wheels 3-3 disposed in close proximity to the side walls, and are mounted correspondingly in pairs upon shafts 5-5. As will be seen from Fig. I, 80 these sprocket wheels are so located within the structure as to determine a circuitous course for the conveyor comprehending a series of vertical loops. The conveyor system may be actuated, for example, by a worm gear couple 6 driving the shaft 5 of the sprockets 3 at the upper left-hand end of the machine. The worm gear couple 6 may be coordinated in any approved manner with a pulley 7, to which power may be applied from any convenient source. Suspended between the conveyor chains 2-2 are a multiplicity of transversely extending carriers 10, in such manner as to be free to swing in passing the various sprockets of 85 the system. These carriers 10, as shown in Fig. II, comprise end brackets 11 having suitably offset lugs for attachment of tie rods 12. These tie rods 12 serve as supports for trays or shelves. The trays may extend 90 across the full width of the machine or they

100

105

may be made in two or more parts or sections such as shown at 13—13. In drying certain materials or articles of manufacture, the smaller trays are found in practice to be 5 more convenient for handling in transferring them from one part of a manufacturing plant to another.

The air within the structure is propelled in a general longitudinal direction over two 10 separate and distinct courses. Such circulation is effected through the instrumentality of oppositely rotating fans 15 and 16 located respectively adjacent opposite ends of the enclosure, and which cooperate with 15 deflecting partitions 17, 18 and horizontal diaphragms 19, 20, by which the courses of the air are definitely determined. An interval is left at the centre of the structure between the inner edges of the diaphragms 20 19, 20, so as to afford an opening for the return flow of the air to the channels 21—22 below said diaphragms. It will be obvious that the direction of circulation in each instance may be readily reversed by changing 25 the rotation of the fans, or such reversals may be made periodical by employing any suitable means for the purpose. In the present embodiment, I have shown the drive of the fans 15 and 16, as being accomplished by a bevel gear connection 25 from 30 a shaft 26 which extends in each instance to the exterior to afford attachment for a driving pulley 27. In addition to their functions previously noted, the partitions 35 17, 18 serve to set apart vertical end passages or channels 28 and 29, through which the terminal runs of the conveyor pass. These passages 28 and 29 are accessible from the exterior through openings 30, 31, of the 40 end walls of the enclosure and are respectively provided with guards or guides 32, 33 which prevent swinging of the conveyor carriers 10, when the trays or shelves 13—13 are being mounted upon, or removed from 45 the conveyor 2. By reason of their isolation from the other portions of the interior of the enclosure, except for the openings through which the carriers of the conveyor 2 enter and emerge, these passages or channels 28, 29 are substantially neutral in so 50 far as the air circulation is concerned.

In order that the flow of the air may be controlled or modified in coursing through the enclosure 1, I have provided at intervals 55 along the length of the same, upright transversely extending partitions 35, 36 which are located between certain vertical runs of the conveyor. These partitions 35, 36, in addition to a function which will be presently described, serve to divide the structure lengthwise into a series of consecutive zonal sections of which there are three shown in the illustration. By referring to Fig. II, it will be seen that each of these partitions 60 comprises a number of baffles in the form

of side plates 37—37, and intermediate plates 38. While any number of such baffles 35—36 may be employed, in the case of machines in which the shelves extend the full width of the enclosure, I prefer 70 to use only the baffles 37—37 at the sides of the structure. By reason of the relative disposal of the baffles 37 of the partitions 35 and 36, with respect to the air propelling fans 15 and 16, it will be observed 75 that the air along the sides of the machine within the intermediate zonal section of the structure is substantially retarded or impeded, so that the flow is diverted more generally toward the centre at 80 said central section. In practice, heretofore, it has been found that the articles supported at the ends of the trays 13—13 invariably dry at a much more rapid rate than those at the centre, this being due to irregularities or variations in the velocity in different parts of the fields of the rotary fans 15, 16 as previously explained. The side baffles 37—37 by reason of their position within the fan fields serve to impede or retard the 85 travel of the air in the region of highest velocity, and to deflect it toward the central region of lower velocity, so that the drying 90 may be rendered more uniform over the width of the enclosure throughout the extent of the trays 13—13. When using the divided trays, I prefer to employ according to the number of subdivisions, one or more intermediate baffles, such as indicated 95 at 38, such additional baffles serving functionally in a manner analogous to that described in connection with the baffles 37—37. The baffles 35—36 may be made either imperforate as shown in Figs. I, II and III, 100 or foraminated as in Fig. IV in any approved way in accordance with the extent of impedance desired. While, according to the showing herein, the control of air flow is confined more directly to the intermediate 105 zonal section of the structure, it will be obvious that the location of the partitions 35 and 36 may be changed so that the range 110 of such control may be made more extensive. The coils represented at 39—39 serve 115 to heat the circulated air in a well known manner.

In the drying of certain articles of manufacture such as, for example, clay rolls which are used in the manufacture of spark 120 plugs, in order to prevent too rapid drying, it has been found advantageous to humidify the air which tends to retard the drying of the outer skin sufficiently to permit the escape of the moisture from the 125 more remote parts of the interior. For the purpose of humidifying the air, I have provided at the back of the fans 15 and 16, transversely extending spray pipes 40 and 41 respectively. The perforations in these 130 pipes extend across the full width of the

machine so as to deliver their charge uniformly to the air. In addition, I have provided in the intermediate zonal section of the structure an auxiliary spray pipe 42, 5 having perforations only within the limits of the widths of the baffle plates 35, 36, so as to assist in effectively retarding the drying of the materials at the end portions of the conveyor trays, see Fig. III.

10 In operation, the materials to be dried are mounted upon the conveyor carriers 10 through the opening 30 at the right-hand end of the structure. Following the direction of the arrow heads on the conveyor in 15 Fig. I, it will be seen that the carriers 10 are advanced toward the interior over the top of the partition 17 and in moving downwardly in the first loop of the conveyor course are subjected to the full blast of the 20 hot air from fan 15, so as to be uniformly raised to the proper drying temperature, and at the same time appropriately humified by the spray from pipe 40. After turning about the lower end of the partition 35 and 25 entering the intermediate zonal section of the structure, the flow of the air is broken up by the baffles of the partition so that the velocity of the air about the end portions of the trays 13—13 is sufficiently retarded with respect to that about their central portions to effect uniform drying, thus 30 obviating all danger of fracture or cracking. In further progress through the intermediate zonal section of the structure, the general conditions just described remain the same except for the application of additional moisture from a spray pipe 42 at the critical regions, and the movement of the articles gradually into the province of the current 35 created by the fan 16. In passing through the final zonal section of the machine, the articles are again subjected to the full blast of air in a direction opposite to that initially applied so as to insure their being uniformly 40 dried on all sides before removal through the discharge opening 31 at the left-hand end of the structure. By proper regulation of heat and moisture, the machine constructed as herein described may be readily 45 adapted for drying many different varieties of manufactures.

Having thus described my invention, I claim:

55 1. A drying machine comprising an enclosure; means for propelling air through the enclosure; and means for modifying the velocity of the air to various extents in passing through different zones of the enclosure by retarding the velocity thereof at the sides of its flow.

60 2. A drying machine comprising an enclosure; means for propelling a stream of air through the enclosure; means for modifying the velocity of the air to various extents in passing through different zones of

the enclosure by retarding the velocity thereof at the sides of the stream; and means for humidifying the air at certain regional points to retard the drying operation.

3. A drying machine comprising in combination an enclosure; rotary fans for propelling air longitudinally through the enclosure; and cooperative means for controlling the flow of the air so that the velocity may be made uniform throughout the field of 70 the fan by retarding that portion of the air current originating at the peripheries of the fans without retarding that portion of the air current originating at the inner portions thereof.

80 4. A drying machine comprising, in combination, an enclosure; a rotary fan for propelling air longitudinally through the enclosures; and upright baffle means at the sides of the enclosure for retarding and deflecting the air flow, so as to make the drying action more uniform over the width of the enclosure.

85 5. A drying machine comprising in combination an enclosure comprehending a number of consecutive zonal sections; a rotary fan for propelling air successively through said zonal sections; and means for controlling the flow of the air so that the velocity may be made uniform throughout the intermediate zonal sections of the series.

90 6. A drying machine comprising in combination an enclosure; means for propelling the air in a general longitudinal direction over separate and opposed courses in opposite ends of the enclosure; and transversely extending partitions located at intervals intermediate the air propelling means, said partitions comprising a series of baffles for modifying the flow of the air at different 100 regions within the enclosure.

105 7. In a drying machine comprising in combination an enclosure; supporting carriers for the articles to be dried; means for progressing said carriers through the enclosure; means for circulating the air within the enclosure; and means for controlling the flow of the air so as to modify its velocity in impinging upon different portions of the carriers.

110 8. A drying machine including in combination an enclosure; supporting carriers for the articles to be dried; means for progressing said carriers through the enclosure; means for circulating the air within the enclosure; means for controlling the flow of the drying medium so as to modify its velocity in impinging upon different portions of the carriers; and means for maintaining, at the same time, various degrees of 115 humidification about different portions of the carriers.

120 9. A drying machine including in combination an enclosure; an endless conveyor tracing a series of vertical loops in a general 125

130

longitudinal direction through the enclosure; a series of transversely extending supporting carriers for the articles to be dried suspended from said conveyor; means for propelling the air through the enclosure in the same general direction as that of the general movement of the conveyor; and inwardly extending baffles disposed at intervals along the side of the enclosure between the vertical runs of the conveyor, said baffles serving to modify the flow of the air along the sides of the enclosure.

10. A drying machine including in combination an enclosure; an endless conveyor tracing a series of vertical loops in a general longitudinal direction through the enclosure; a series of transversely extending supporting carriers for the articles to be dried suspended from said conveyor; means for propelling the air through the enclosure in the same general direction as that of the general movement of the conveyor; inwardly extending baffles disposed at intervals along the side of the enclosure between the vertical runs of the conveyor, said baffles serving to modify the flow of the air along the sides of the enclosure; and spray pipes having perforations restricted to the regions of the modified air flow.

11. A drying machine including in combination, an enclosure; an endless conveyor tracing a circuitous course through the enclosure; a series of transversely extending carriers suspended from said conveyor; supporting trays or shelves for the articles to be dried removably mounted upon said carriers; means for circulating the air within the enclosure in the same general direction as that of the general movement of the conveyor; and means for retarding the flow of the air along the sides of the enclosure to modify its velocity in impinging upon the ar-

ticles at the regions of the ends of the supporting shelves of the conveyor carriers.

12. The combination with a drying machine including an enclosure, means for creating an air stream therethrough in which the velocity of the air flow varies in different portions, and an article support extended transversely of the direction of flow of the air stream; of means interposed in said air stream to retard the flow of the air at either side of the stream without retarding the flow along the center line of the stream, whereby to effect a uniform drying of articles supported upon any portion of the carrier.

13. A drying machine comprising in combination an enclosure comprehending a number of zonal sections, rotary fans for propelling air longitudinally through the enclosure, and co-operative means for establishing uniform velocity of air-flow through said enclosure by merging that portion of the air currents originating at the peripheries of the fans with that originating at the inner portions thereof.

14. A drying machine comprising in combination an enclosure comprehending a number of zonal sections, rotary fans for propelling air longitudinally through the enclosure in opposed directions, and co-operative means for establishing uniform velocity of air-flow through said enclosure by merging that portion of the air current originating at the peripheries of the fans with that originating at the inner portions thereof, said co-operative means comprising side and intermediate baffles disposed in spaced relation.

In testimony whereof, I have hereunto signed my name at Philadelphia, Pennsylvania, this 20th day of October, 1920.

BERTRAND A. PARKES.
